CLAIM

The ornamental design for an inner container for a compact, as shown and described.

DESCRIPTION

FIG. 1 is a front, right-side, and top view of an inner container for a compact showing the new design.

FIG. 2 is a top plan view of the inner container for a compact.

FIG. 3 is a front elevation view of the inner container for a compact.

FIG. 4 is a right-side elevation view of the inner container for a compact.

FIG. 5 is a cross sectional right-side view, better showing the profile of the top.

FIG. 6 is a rear elevation view of the inner container for a compact.

FIG. 7 is a left-side elevation view of the inner container for a compact.

FIG. 8 is a bottom plan view of the inner container for a compact; and,

FIG. 9 is a front, right-side, and top view showing the inner container for a compact in a position of use inside a compact drawn in broken lines.

(Continued)

The broken lines illustrating a compact depict environment and form no part of the claimed design. All other broken lines depict portions of the inner container for a compact that form no part of the claimed design.

1 Claim, 9 Drawing Sheets
